Application January 11, 1950, Serial No. 137,968

Claims priority, application Great Britain
January 13, 1949

7 Claims. (Cl. 66—1)

1

This invention concerns a hand appliance which is arranged to be attached to a chain and affords a hand grip permitting the chain to be hauled manually. An important application of the invention is to knitting machines. Knitting machines, and especially circular knitting machines of the type known as seamless hose or half hose machines, are commonly provided with a patterning or timing chain built up from a multiplicity of readily detachable links each of which is provided at one end with an integral hook which hooks on to a cross bar at the end of the adjacent link; at the requisite points in the length of this chain the links are provided with studs or cams which as the chain is periodically racked round serve to time or initiate various automatic operations of the machine. For details of a widely-used chain of this type, reference may be made to the specification of British Letters Patent No. 335,725. It is often necessary to pull the chain round by hand when it is desired to bring the machine to a predetermined phase in its automatic operations (e. g. when it is desired to interrupt the production of a stocking or sock at an intermediate stage and to cause the machine to commence the production of a new stocking or sock). This necessitates the operator grasping a portion of the chain with his or her hand, pulling the chain (usually downwards) as far as circumstances permit, then taking a fresh grip and again pulling the chain and so on. It is unavoidable that grease or oil on the chain should thereby be transferred to the operator's hand and this grease or oil is eventually transferred to the work under production, and this is disadvantageous.

An object of this invention is the provision of a hand appliance which may be fitted to the timing or patterning chain of a knitting machine and which affords a hand grip of which the operator may avail himself or herself to pull the chain round thereby avoiding direct hand contact with the chain. It will be appreciated however that the utility of such a device is not restricted to knitting machines and that it may be employed in other circumstances in which it is desired to haul a chain by hand, for example in pulley block systems employing chains, and chain hoists.

The invention therefore provides a hand appliance for use in hauling a chain by hand, constructed and arranged to be mounted on the chain and itself affording a hand grip, which appliance incorporates means for locking it to the chain against relative movement in one direction but permitting of relative movement in the other direction. By relative movement there is meant

movement of the chain, or of the appliance, that causes the location at which the appliance is mounted on the chain to shift along the latter. Thus, when the appliance is mounted on a vertical

5 lap of a chain, travel of the chain down past the appliance and movement of the appliance up the chain, both constitute relative movement in the same direction. It will therefore be appreciated that, considering the application of the appliance to the vertical lap of a chain (as for example in a seamless hose or half hose machine) the chain may freely travel down through the appliance when the latter is stationary, and the appliance may freely be raised up the chain, but if the appliance, when elevated, is forced downward it locks on the chain and causes the latter to be moved downwards.

The utility of the appliance in connection with knitting machines, in particular, will therefore be apparent.

The locking means is preferably automatic in operation, although it may be of a kind requiring manual operation as for example the movement of a catch or the like (or of a member operating such a catch) between "locked" and "free" positions. If the locking means is automatic in operation, the appliance preferably incorporates manually-operable release means for the locking means. Furthermore, the locking means may 10 have a reversing control associated with it for reversing its action so that the direction in which relative movement is inhibited may be reversed at will. For example, assuming the appliance to be associated with a vertical lap of a chain, either 15 the control may be so operated that the chain is free to travel down through the appliance and the latter, when raised, lifts the chain with it, or the control may be so operated that these conditions are reversed and the chain is free to travel 20 up through the device and the latter, when forced downwards, carries the chain down with it. The locking means preferably comprises pawl and ratchet mechanism and, whether automatically or manually operable, it advantageously incorporates a sprocket which engages the chain and either rotates or is prevented from rotating according to whether the locking means is inoperative or operative. The ratchet may be constituted by the chain itself, or by a ratchet wheel attached to the sprocket, or by the sprocket itself. If the ratchet is constituted by the chain itself, the pawl is desirably arranged to engage the cross bars of the chain links which cross bars therefore serve as ratchet teeth. If the ratchet 25 is a ratchet wheel, or the sprocket itself, then the

ratchet mechanism in effect constitutes a free wheel mechanism associated with the sprocket but free wheel mechanisms that do not incorporate a pawl and ratchet (e. g. having wedging balls or rollers) are known and may be used in this invention.

Specifically, the invention provides a hand appliance for use in hauling a chain and affording a hand grip, which appliance comprises a hollow member affording through its interior a passage-way for the passage of the chain, guides for engaging the chain in its passage through the passage-way and for locating the appliance in relation to the chain, a sprocket on said member for meshing with the chain, and a pawl permitting rotation of the sprocket in one direction only.

The invention further includes a knitting machine having a patterning or timing chain of the type referred to, a hand appliance, having the features herein specified, on the chain, and a stop on the machine restricting movement of the appliance in the direction of normal travel of the chain.

The foregoing and other features of the invention set out in the appended claims are incorporated in the hand appliances which will now be described (as examples of preferred constructions) with reference to the accompanying drawings in which:

Figure 1 is a front elevation, Figure 2 a side elevation, and Figure 3 a rear elevation of one hand appliance;

Figure 4 is a section taken on the line IV—IV in Figure 1;

Figure 5 is a section taken on the line V—V in Fig. 2.

Figure 6 is a view looking on the bottom end of the appliance;

Figure 7 is a front elevation, Figure 8 a side elevation, and Figure 9 a rear elevation of a further appliance;

Figure 10 is in longitudinal section taken on the line X—X in Figure 7;

Figure 11 is a section taken on the line XI—XI in Fig. 8;

Figures 12, 13 and 14, are sectional views showing, respectively, three modified constructions.

In this description, it is convenient to consider the appliance (which is preferably made of metal) in the upright attitude which it occupies when applied to the timing chain of a seamless hose or half hose machine. In the construction shown in Figs. 1-6, the appliance is in the main of hollow tubular form comprising a conveniently-shaped handling portion 1 and providing in its interior an elongated vertical tunnel 2 for the downward passage of the chain 3 in contact with a guide plate 4 forming what may be regarded as the back of the tunnel, and since the hooks 6 of chain links 5 in timing chains of the type under consideration usually protrude slightly at the back of the chain as shown at 7 in Figs. 2 and 4, this guide plate 4 is formed with a centrally disposed vertical groove 8 to accommodate these protruding parts 7 of the hooks. The chain 3 is further guided in contact with this guide plate 4 by a sprocket 9 hereinafter described and by a vertical guide rib 10 which is attached to the front wall 11 of the tunnel and is arranged to engage the front of the chain links, the width of this rib 10 being such that forwardly protruding studs 12 on the side bars 13 of the chain links pass at either side of it. Additionally, the tunnel is sufficiently wide to accommodate side studs 14 which may be pro-

vided on the side bars 13 of the links and which protrude from the edges of the chain in the general plane of the chain links 5.

A small distance below the top of the tunnel, 5 but above the top end of the guide rib 10 just mentioned, the tunnel is formed with an enlargement or pocket 15 in which the chain sprocket 9 is pivotally mounted for movement about a horizontal axis 16 which is transverse to the length of the tunnel. This sprocket 9 has its teeth 17 constructed and arranged to mesh with the links 5 of the chain 3 and it serves to hold the chain at this location against the rear guide plate 4. Associated with the sprocket 9 there 15 is a pawl 18 which is pivoted at 19 and is urged by a spring to engage between the sprocket teeth. This pawl 18 is so arranged that it will yield to permit the sprocket 9 to rotate as the chain 3 passes down the tunnel 2 and as the hand appliance 20 is being shifted up the chain, but it is also so arranged that it prevents the sprocket 9 from rotating in such reverse direction as would permit the chain travelling up through the tunnel and the hand appliance being moved down the chain. The sprocket therefore acts as a ratchet 25 wheel, and it will be appreciated that the hand appliance when fitted to the chain does not prevent the chain travelling downwards through it in the normal operation of the machines (the 30 appliance then resting on a bottom stop provided for it on the machine) but when it is desired to pull the chain round by hand the appliance may be grasped by hand, lifted up the chain (during which movement the sprocket 9 revolves), and then pulled downwards; this downward pull carries the chain 3 with it because the pawl 18 then prevents the sprocket 9 from rotating. The pawl 18 is releasable by means of a thumb-piece 21 protruding through a slot 22 in the front wall 23 of pocket 15.

The front wall 11 of the tunnel 2 may be continued above the pocket 15 in order to provide a thumb guard which will prevent the thumb of that hand which grasps the appliance being caught by the chain studs.

In the construction shown in Figs. 7-10, the main body of the appliance (affording tunnel 2) is indicated at 1' and the back plate at 4'. The guide rib 10 is replaced by a sprocket 24, the main body 1' being modified in shape to accommodate this additional sprocket and also formed into a finger guard as shown at 25 which will prevent the thumb of that hand which grasps the appliance being caught by the chain studs. The two sprockets 9 and 24 are pivotally mounted for movement about horizontal axes which are transverse to the length of the tunnel, the spindles 26, 27 of said sprockets being located in the slots 28 and 29 in the front portion 1'. The slots 28 and 29 are used instead of holes merely to enable the sprockets 9 and 24 to be assembled easily, as each spindle and its sprocket may then be made integral and inserted in the front portion 1' before the back plate 4' is assembled. 60 This will readily be appreciated from an inspection of Fig. 11. The two sprockets 9, 24 have their teeth constructed to mesh with the links of the chain 3 and also serve to hold the chain against the back plate 4'. As best shown in Figs. 9 and 10 the back plate 4' is cut away at 30 to allow the hooks 6 of the chain links 5 to protrude through the plate 4' whilst the side bars 13 of the links slide along the face of the plate. Associated with the sprockets 9, 24 there is a 65 pawl 18' pivotally mounted on the spindle 27 of

sprocket 24 and urged by a spring 32 to engage the teeth of the sprocket 9. This pawl 18' is so arranged that it will yield to permit the sprocket 9 to rotate as the chain 3 passes down the tunnel 2 and as the hand appliance is being shifted up the chain, but it is also so arranged that it prevents the sprocket 9 from rotating in such reverse direction as would permit the chain 3 travelling up through the tunnel 2 and the hand appliance being moved down the chain. The pawl 18' is made with one extremity formed into a finger piece 21' which protrudes through a hole 22' formed in the front portion 1', and during the normal working of the machine when the chain is moving downwards or when the appliance is being moved up the chain preparatory to pulling the chain round, the finger piece 21' oscillates freely to the position shown by the chain dotted lines in Fig. 10. Now as is well known it is often necessary to move the chain in the reverse direction from that in which it moves when the machine is normally working, this can be achieved simply by gripping the specially formed part 33 of the front portion 1' and the finger piece 21' together; this results in the end 34 of the pawl 21' engaging the teeth of the sprocket 9 thus preventing the latter from rotating when the appliance is moved upwards and so carrying the chain with it.

If it is desired to render the action of the device reversible, as shown in Fig. 12, there may be two oppositely-acting pawls 18a, 18b and a reversing control comprising a bluff or pawl lifter 35 movable manually to render either selected pawl inoperative. The pawls are urged towards the sprocket 9 by springs 20a, 20b, and carry pins 36a, 36b. The bluff 35 is capable of being rocked about the spindle 16 of the sprocket by a control lever 21a protruding through a slot 22a in the body 1a and is formed with opposed cam-like arms 37a, 37b, for acting on the respective pins 36a, 36b to move the required pawl to an inoperative position in which its pin is temporarily retained in a notch in the end of the arm. In the drawing, pawl 18a is bluffed or inoperative.

Alternatively, as shown in Fig. 13 there may be two sprockets 9 and 24 spaced apart along the length of the chain, a common pawl 18c operable on one sprocket to prevent its rotation in one direction and on the other sprocket to prevent its rotation in the opposite direction, and manually-operable means for causing the pawl to operate on either selected sprocket at will. Pawl 18c is pivoted at 38 at an intermediate point in its length, and at one end is provided with a pin 39 engaged in the fork 40 of a hand lever 21b pivoted at 41 and protruding through a slot 22b in the casing 1b. A tension spring 42 serves to cause the pawl 18c to move over the dead centre position with a snap action and then serves to bias the pawl towards the selected sprocket.

In a modification (not illustrated) of this last construction there may be a pawl for each sprocket and manually-operable means for rendering either selected pawl inoperative (and the other operative) at will.

Fig. 14 illustrates a construction in which the ratchet is constituted by the chain 3 itself. The double-acting pawl 18d is pivoted at 38 and is provided with opposed pawl arms 43a, 43b either of which may be swung (against the action of one or other of the release springs 44a, 44b) to a position in which it is placed to engage the cross bars of the chain links. This movement

is effected by hand lever 21c protruding through slot 22c in casing 1c, and it will be seen that whereas the operative pawl arm will, when engaged in the chain, prevent movement of the appliance along the chain in one direction yet upon slight movement of the appliance in the reverse direction the pawl arm will quickly free itself from the chain (under the action of one of the release springs) unless held in operation by pressure on the hand lever 21c. However, it is within the scope of the invention to provide a snap action spring 42' which, like spring 42 in Fig. 13, causes the pawl 18d to snap over to either of its extreme positions and to remain therein until moved by hand lever 21c. Elements 10' are guide blocks for holding the chain against the back plate 4c.

We claim:

1. A hand appliance adjustable along a chain 20 of generally flat open links for pulling purposes, comprising a tubular casing shaped exteriorly to fit the user's handgrip, a longitudinal guideway in such casing comprising a flat face to guide the open links of the chain, a toothed sprocket 25 freely rotatable in said casing and having its teeth extending successively into said guideway as it rotates, to mesh with successive links of the chain, a spring-pressed pawl in said casing normally obstructing reverse rotation of said sprocket, and a trip member projecting out of the casing for withdrawal of the pawl from the said sprocket.

2. A hand appliance adjustable along a chain 30 for pulling purposes, comprising a trough-sectioned casing with an enlargement at one, an attached flat plate closing in the otherwise open side of the trough and enlargement, a central rib or web in the trough, with its free edge spaced from said attached plate to form a guideway for the chain, a toothed sprocket freely rotatable in said guideway with its teeth, as they rotate, successively passing into the line of said enlargement and having one of its limbs projecting out of the casing through a slot, and a spring normally holding the pawl in the path of the sprocket teeth to prevent reverse rotation.

3. A pulley device comprising a hanging chain 50 composed of flat co-planar open links hooked together, at least some of which are forwardly-extending studs or spurs on one face and some of which have laterally-extending arms on the sides, a trough-sectioned casing with an enlargement at its upper end, an attached flat plate closing in the otherwise open side of the trough and enlargement, a central rib or web in the trough, with its free edge spaced from said attached plate to form a guideway for the chain links with their said studs and arms, a toothed sprocket freely rotatable in said enlargement with its teeth, as they rotate, successively passing into the links of the chain, an L-shaped pawl mounted in said enlargement and having one of its limbs projecting out of the casing through a slot therein, and a spring normally holding the pawl in the path of the sprocket teeth to prevent reverse rotation.

4. A hand appliance adjustable along a chain 70 of flat open links for pulling purposes comprising a trough shaped casing to receive the chain in its trough, and formed exteriorly to fit the user's hand, a finger guard extending from the upper part of said casing to shield the user's fingers from the entrance end of the trough, an attached flat plate to close the otherwise open

side of the trough, a pair of toothed sprockets in the trough, mounted on parallel transverse axes, with their peripheries adjacent the inner face of such plate as they rotate, a pawl mounted on the axis of one sprocket and movable into and out of the teeth of the other sprocket to obstruct reverse rotation of the said other sprocket, spring means in the casing urging the pawl into said teeth, and a trip lever on said pawl extending out of the casing.

5. A hand appliance adjustable along a chain of generally-flat open links for pulling purposes, comprising a tubular casing shaped exteriorly to fit the user's handgrip, a longitudinal guideway in such casing comprising a flat face to 10 guide the open links of the chain, a toothed sprocket freely rotatable in said casing and having its teeth extending successively into said guideway as it rotates, to mesh with successive 15 links of the chain, a pair of pawls in the casing 20 with spring means urging them into the teeth of the sprocket at opposite sides to obstruct reverse rotation of the sprocket, a pivoted pawl-lifting member on the axis of the sprocket and engaging the pawls selectively, and a trip lever 25 on said pawl-lifting member extending out of the casing through a slot therein.

6. A hand appliance adjustable along a chain of generally-flat open links for pulling purposes, comprising a tubular casing shaped exteriorly to 30 fit the user's handgrip, a longitudinal guideway in such casing comprising a flat face to guide the open links of the chain, a pair of sprockets on parallel transverse axis in the casing and meshing 35 with the chain, a pivoted pawl movable se-

lectively into the teeth of either sprocket to obstruct its reverse rotation, a spring urging the pawl into its selected position, and a pivoted trip lever extending out of the casing and in operative connection with said pawl to withdraw it from the respective sprockets.

7. In a circular knitting machine, a hanging downwardly-moving pattern chain composed of flat, co-planar open links, a tubular casing shaped exteriorly to fit the user's handgrip, a longitudinal guideway in such casing with at least one flat face to guide the open links of the chain, at least one toothed sprocket freely rotatable in said casing and having its teeth extending successively into said guideway as it rotates, to mesh with successive links of the chain, at least one spring pressed pawl in said casing normally obstructing reverse rotation of said sprocket, a trip member projecting out of the casing for withdrawal of the pawl from the said sprocket, and a stop member in the path of the downwardly-moving hand-grip.
